UNITED STATES PATENT OFFICE.

ADOLPH COHEN, OF NEW YORK, N. Y.

DESIGN FOR RUFFLING.

SPECIFICATION forming part of Design No. 21,993, dated November 15, 1892.

Application filed September 3, 1892. Serial No. 445,014. Term of patent 3½ years

To all whom it may concern:

Be it known that I, ADOLPH COHEN, a citizen of the United States, residing at New York city, in the county and State of New York, have invented and produced a new and original Design for Ruffling, of which the following is a specification, reference being had to the accompanying drawings, forming a part of this specification.

Figure 1 represents the ruffling in perspective and as embodying the features of the design, and Fig. 2 is a vertical section taken through the body portion of the design.

The leading feature of the design consists in a skirt figure A, having a fluted or ruffle-like appearance, which figure seemingly drops

downward in graceful folds from the base of a crowning figure B, the latter figure having also a fluted or ruffle-like appearance; but the crowning figure B curves outward at a decided angle to the skirt figure, which figure hangs, essentially, perpendicularly. In the complete design the two figures A and B jointly form a neck figure of circular contour.

I claim—

The design for ruffling, substantially as herein shown and described.

ADOLPH COHEN.
